UNITED STATES PATENT OFFICE

124,694

DESIGN FOR A RECEPTACLE FOR FALSE TEETH AND REMOVABLE BRIDGES

Morton Hague, Chicago, Ill.

Application September 6, 1940, Serial No. 94,830

Term of patent 14 years

To all whom it may concern:

Be it known that I, Morton Hague, a citizen of the United States, residing at Chicago, in the county of Cook and State of Illinois, have invented a new, original, and ornamental Design for a Receptacle for False Teeth and Removable Bridges, of which the following is a specification, reference being had to the accompanying drawing, forming part thereof.

Figure 1 is a perspective view of a receptacle for false teeth and removable bridges, showing my new design, with the cover closed.

Figure 2 is a similar view but with the cover in open position.

The other side of the article shown is substantially like the side shown.

I claim:

The ornamental design for a receptacle for false teeth and removable bridge, substantially as shown and described.

MORTON HAGUE.
